METHOD AND APPARATUS FOR DRAWING
METAL

Aaron Simons, Bronx, N. Y.

Application April 26, 1940, Serial No. 331,692

15 Claims.

(Cl. 205—1)

This invention relates to machines for drawing metal strips, sheets and the like between rotatable die members or rolls of extremely small diameter adjustable toward and from each other to control the reduction in the workpiece drawn through the apparatus; and the object of the invention is to provide an apparatus of the character described wherein the die members or rolls are restrained against bending in any direction, and are retained in fixed position while rotating on their axes, and wherein longitudinal friction bearings or backings are provided for the die members or rolls which bearings reciprocate back and forth in opposed directions to each other while said die members or rolls are rotated, thereby controlling frictional relationship in an apparatus of the class described; a further object being to provide reciprocating longitudinal friction bearings or backings for rotatable rolls which support the rolls throughout the full working length of the rolls; and with these and other objects in view the invention consists in the method of producing strips or sheets and in an apparatus as more fully hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic sectional view through a part of an apparatus or rolling mill made according to my invention.

Fig. 2 is a partial section on the line 2—2 of Fig. 1; and

Fig. 3 is a partial section on the line 3—3 of Fig. 1.

My present invention relates to a machine of the general type and kind more fully disclosed in, for example, my prior application, Ser. No. 269,373, filed April 22, 1939, of which this application constitutes a continuation in part.

It is the purpose of my invention to provide an apparatus for drawing strip or sheet material and a method of producing such material by utilizing non-reciprocating rolls which are arranged in reciprocating friction bearings are backings, with independent means for rotating said rolls, thereby facilitating the production of drawn products having smooth finish, or in other words, unmarred surfaces. This result is made possible by the use of combined rotatable rolls and reciprocating bearings or backings. Furthermore, it will be apparent that by utilizing different drives for the rolls, the rolls may be rotated at surface speeds materially different from the speed of travel of the outgoing reduced product, thereby facilitating the drawing of the workpiece between the rolls. It will also be ap-

parent that the combined rotary movement of the rolls and reciprocating movement of the backings will materially reduce the frictional surface resistance between the rolls and their backings, and permit the rolls to be rotated at all times in their respective bearings or backings.

In Fig. 1 of the drawing is shown a diagrammatic partial sectional view through a machine substantially of the type and kind disclosed in my application hereinbefore referred to; such parts only of the machine being shown as are necessary to illustrate the operation and structural arrangement of the die members or rolls and their longitudinal friction bearings or backings. At 10 is shown part of the base or frame 10 of the machine in which is supported a shaft 11 driven from a suitable motor. On this shaft is arranged a small gear 12 operatively engaging large gears 13, only one of which is indicated. The gears 13 are disposed in a housing 14 adjacent to and form part of the frame structure of the machine. The gears 13 are utilized to drive the drums supporting the workpiece and for drawing the workpiece in either of two directions through the machine as taught in said prior application. A schematic showing of the drums referred to is indicated at 13a, 13b, in Fig. 2 of the drawing, and the shaft of one of these drums is indicated at 13c. The workpiece or strip is indicated at 13d.

Arranged upon the frame is a suitable casing 15 in which is supported a shaft 16 driven from the shaft 11 through a chain and sprocket construction as at 17. In the housing 15 is also supported a short shaft 18 driven from the shaft 16 through gears 19 and 20 on the shafts 16 and 18 respectively. Arranged upon the shaft 18 within the housing 15 is an oblique cylinder 21 which is adapted to impart reciprocating movement to bearings or backings 22, 23 of die members or rolls 24, 25. The cylinder 21 has extending arms 26, 27 operating in drive rods 28, 29 respectively. The rods 28, 29 extend through at least one end of the casing 15 and the rod 28 operates in a bearing plate 30 which also forms a bearing for the shaft 16 and the roll 25.

At 31 is shown a die block arranged upon the frame 10 of the machine, and the shaft 16 extends into and through this block and is arranged in suitable bearings 32 therein. On the shaft 16 is a gear 33 which meshes with a gear 34 arranged upon the die member or roll 25, whereby the same is rotated. The other or upper roll 24 is placed in operative engagement with the shaft 16 through a gear 35, an intermediate gear 36, and a gear 37. The gear 36 is mounted upon pivotally coupled links, as indicated in Fig. 2, so as to compensate for the slight vertical adjustment of the roll 24 with re-

spect to the roll 25 in gaging the spacing of said rolls one from the other in controlling the reduction in thickness of the workpiece to be drawn between said rolls.

At 38 is shown a vertically adjustable block with which is coupled the friction bearing or backing 22 and roll 24. The block 38 is adjusted vertically through the medium of a hand wheel 39, on the shaft 40 of which are worms operating in connection with worm gears 41. The latter are arranged on screw rods 42 which are coupled with the block 38. The specific structure of this vertically adjustable block and the manner of its mounting is also disclosed in detail in the prior application and forms no direct part of the present invention aside from indicating a means of adjusting the parts.

Upon the block 31 is arranged a main support or backing 43 which may be of any desired construction, and particularly of such material as to form a proper bearing and mounting for the reciprocating bearings or backings 22, 23. The latter seat in recesses formed in the support 43 as well as a corresponding support 43a supported on the block 38.

The protruding ends of the backings 22, 23 are channeled to receive fork-shaped pins 44 and 45 respectively. These pins are supported upon and movable with the rods 28 and 29. While the relationship between the pin 45 and backing 23 is relatively fixed, it will appear that the forked pin 44 is provided to compensate for vertical adjustment of the upper backing 22. It will of course be understood that the end portion 29a of the rod 29 is of O-frame construction so as to envelope the gears as well as the bearing plate 30, note for example, Fig. 3, and provide for the reciprocating movement which is imparted to the backing 23.

Movable with the block 38 is a bracket 38a forming a bearing and support for the outer end of the roll 24. In the present construction, it will be understood that the die members or rolls 24 and 25 are maintained in a fixed position longitudinally with respect to each other, or in other words are not reciprocated. However, these rolls are rotated through the gears employed, and by changing the ratio of gearing, these rolls may be driven at different speeds. In some instances, the surface speed of the rolls 50 may be less than the speed of the outgoing drawn product. However, in operating upon some types and kinds of workpieces, the speed of rotation of the rolls may be equal to or even greater than the movement of the outgoing product.

In the operation of the machine, it will be understood that the block 38 will be adjusted to provide the desired or predetermined spacing between the rolls 24, 25. As the strip is drawn between the rolls from one of the drums actuated through one of the gears 13, the backings 22, 23 are reciprocated back and forth in opposite directions to each other and longitudinally of the axes of the rolls while said rolls are being rotated in the manner heretofore described. This sliding reciprocating movement of the backings will sufficiently reduce the frictional surface resistance between the rolls and their respective backings to prevent binding action and to permit the rolls to rotate at the desired speed to effect the reduction of the workpiece without marring or defacing the workpiece.

Where the initial workpiece is comparatively thick and a great reduction in thickness is re-

quired, after the workpiece has been drawn through the machine in one direction, suitable means may be provided to throw the opposed drum into operative position so as to again draw the workpiece through the machine in a direction opposite to the first mentioned direction. It will be understood that suitable adjustment of the block 38 has been made to provide the closer spacing of the rolls 24, 25 to produce the further reduction in thickness of the workpiece constituting the pre-drawn product.

It will of course be apparent that in machines of the type and kind under consideration, many devices and mechanisms are employed to control and regulate the several parts, and in lubricating the parts including the workpiece, but as such structures form no direct part of the present invention the same have been eliminated in order to simplify the disclosure of the parts or elements which are employed to carry my improved method into effect.

It will be understood that the die members, rolls, or other elements, have overlapped portions which are arranged in fixed relationship to each other longitudinally of the axes thereof to define what may be termed a working length of the rolls within the limits of these overlapped portions. The reciprocating bearings or backings operate within this working length of the rolls to maintain a constant bearing or backing therefor. In the same sense, the fixed or stationary supports are also extended to fully and amply cover this working length of the rolls. In different capacity machines, the structures will be made to suit the workpieces to be handled in the machine, and in this respect, the present illustration is representative of only one type and kind of machine, and even here the illustration is to be regarded as more diagrammatic than otherwise.

Having fully described my invention, what I claim as new and desire to secure by Letters Patent is:

1. An apparatus for drawing elongated workpieces to reduce the thickness thereof, comprising two relatively adjustable die members between which a workpiece is drawn, means independent of the workpiece for rotating said die members while maintaining fixed relationship to each other, a backing for each die member, and means for reciprocating said backings in opposite directions to each other and longitudinally of the die members while said die members are rotated.

2. An apparatus for drawing elongated workpieces to reduce the thickness thereof, comprising two relatively adjustable die members between which a workpiece is drawn, means independent of the workpiece for rotating said die members while maintaining fixed relationship to each other, a backing for each die member, means for reciprocating said backings in opposite directions to each other and longitudinally of the die members while said die members are rotated, and means to adjust one of said die members including the backing therefor toward and from the other die member and backing to control and regulate spacing between said die members.

3. An apparatus for drawing elongated workpieces to reduce the thickness thereof, comprising two relatively adjustable die members between which a workpiece is drawn, means independent of the workpiece for rotating said die members while maintaining fixed relationship to each other, a backing for each die member,

means for reciprocating said backings in opposite directions to each other and longitudinally of the die members while said die members are rotated, and other fixed backings in which the first named backings are slidably mounted.

4. An apparatus for drawing elongated workpieces to reduce the thickness thereof, comprising two elongated rolls arranged in parallel relationship, means adjusting the rolls with respect to each other to control spacing therebetween in governing the reduction formed in the thickness of a predetermined workpiece drawn between said rolls, means for drawing a workpiece between the rolls, means independent of the workpiece for rotating the rolls, longitudinal friction bearings for said rolls, means for reciprocating the bearings in opposite directions to each other longitudinally of the axes of said rolls and maintaining the bearings in engagement with the working length of the rolls, and means arranged longitudinally of the working length of the rolls forming supports for said bearings in which said bearings are slidably mounted.

5. An apparatus for drawing elongated workpieces to reduce the thickness thereof, comprising two elongated rolls arranged in parallel relationship, means adjusting the rolls with respect to each other to control spacing therebetween in governing the reduction formed in the thickness of a predetermined workpiece drawn between said rolls, means for drawing a workpiece between the rolls, means independent of the workpiece for rotating the rolls, longitudinal friction bearings for said rolls, means for reciprocating the bearings in opposite directions to each other longitudinally of the axes of said rolls and maintaining the bearings in engagement with the working length of the rolls, means arranged longitudinally of the working length of the rolls forming supports for said bearings in which said bearings are slidably mounted, and a single driven element for simultaneously imparting reciprocating movement to said bearings.

6. In a rolling mill for reducing the thickness of an elongated workpiece, a pair of working rolls arranged in parallel relation and between which a workpiece passes, a pair of backings for said rolls, means for reciprocating said backings in opposite directions to each other and parallel to the axes of said rolls while maintaining the rolls against longitudinal axial movement with respect to each other, and means independent of the workpiece for rotating said rolls upon their axes and while said bearings are reciprocated longitudinally of the rolls.

7. In a rolling mill for reducing the thickness of an elongated workpiece, a pair of working rolls arranged in parallel relation and between which a workpiece passes, a pair of backings for said rolls, means for reciprocating said backings in opposite directions to each other and parallel to the axes of said rolls while maintaining the rolls against longitudinal axial movement with respect to each other, means independent of the workpiece for rotating said rolls upon their axes and while said bearings are reciprocated longitudinally of the rolls, means for adjusting the spacing of the rolls to control the reduction in a predetermined workpiece to be passed through the machine, and means for drawing a workpiece between said adjusted and rotated rolls.

8. In a rolling mill, a pair of working rolls between which a workpiece passes, supporting bearings for said working rolls, means independent of

the workpiece for rotating said rolls, and means for reciprocating said bearings parallel to the axis of said rolls to reduce friction between the bearings and rolls.

5. 9. The method of controlling frictional relationships in a pull-mill, which includes the steps of supporting the working rolls throughout their operative length, pulling a workpiece between said rolls, rotating said rolls independently of said workpiece, and moving the working roll supports parallel to the axis of said rolls while said rolls are rotated.

10. The method of operating a strip mill which includes the steps of supporting the working rolls throughout their operative length, maintaining the rolls in predetermined fixed relationship with respect to each other, reciprocating the working roll supports parallel to the axis of said rolls, pulling a strip through said working rolls, and rotating the rolls in the supports independently of said strip.

15. 11. The method of controlling frictional relationship in drawing elongated workpieces, which includes the steps of supporting each roll of a pair of working rolls throughout its operative length in a backing reciprocated parallel to the axis of the rolls while rotating the rolls within said bearings independently of the passage of a workpiece between said rolls.

20. 12. The method of reducing the thickness of an elongated workpiece which includes the steps of supporting a pair of dies in predetermined spaced parallel relationship to each other throughout their operative length, moving die supports and backings parallel to the axis of the dies in opposite directions to each other while rotating the dies within said supports in controlling frictional relationship while pulling a workpiece between said dies independently of the rotation of said dies.

25. 13. The method of reducing the thickness of an elongated workpiece, comprising mechanically drawing a workpiece between a pair of die members, supporting the die members throughout their operative length, and decreasing the frictional surface resistance between said supports and said die members by reciprocating the supports for the die members parallel to the axes thereof while rotating the die members on their axes, thereby facilitating the drawing of the workpiece between said rotated die members.

30. 14. The method of reducing the thickness of an elongated workpiece, comprising mechanically drawing a workpiece between a pair of die members, supporting the die members throughout their operative length, and decreasing the frictional surface resistance between said supports and said die members by reciprocating the supports for the die members parallel to the axes thereof while rotating the die members on their axes independently of the drawn workpiece, thereby facilitating the rotation of said die members in their respective supports.

35. 15. The method of reducing the thickness of an elongated workpiece, comprising mechanically drawing a workpiece between a pair of elements rotated independently of the drawn workpiece and maintained in predetermined spaced and longitudinal relationship with respect to each other, while reciprocating backings for said elements parallel to the axes thereof and in opposite directions to each other, and reciprocating said backings in stationary bearings extending throughout the operative length of said elements.
